UNITED STATES PATENT OFFICE.

CHARLES H. BEELER, JR., OF PHILADELPHIA, PENNSYLVANIA, ASSIGNOR
TO THE MACKELLAR, SMITHS & JORDAN COMPANY, OF SAME PLACE.

DESIGN FOR TYPE.

SPECIFICATION forming part of Design No. 16,425, dated December 29, 1885.

Application filed October 2, 1885. Serial No. 172,855. Term of patent 14 years.

To all whom it may concern:

Be it known that I, CHARLES H. BEELER, Jr., (assignor to the MACKELLAR, SMITHS & JORDAN COMPANY,) of the city and county of

5 Philadelphia, Pennsylvania, have invented and produced a new and original Design for a Font of Printing-Type, of which the following is a specification.

The nature of my design is clearly shown

10 in the accompanying typographic impression, to which reference is made; and it consists of an open-face letter composed of a light line upon the left, a light line upon the top, and a heavy line upon the right and below, these

15 lines in the greater part of the letters shown not departing from a right line. In the C, G, O, Q, and S the left-hand portion of the letters is composed of an inclined line forming a continuation of the top line, followed by a vertical

20 line, and this in turn by an inclined line joining the heavy line below. In the U the lower portion of the left-hand portion of the letter is inclined, as shown, extending from the vertical portion to the heavy bottom line below.

25 In the X the left-hand portion of the letter is composed of two lines inclined in opposite directions and meeting about centrally. In the Y the upper portion on the left is inclined, as shown; and in the Q the left-hand portion of

30 the letter is inclined, followed above and below by the short vertical lines connecting with the light line above and the heavy line below. In the D, O, Q, S, and U the right-hand portion of the letters is composed of an inclined line,

35 followed by a vertical line, succeeded by an inclined line in the C and G. This formation characterizes the upper and lower portions of the letters. In the B and R the rounding portion of the letters is similar, but joined in

40 the center, as shown. In the P the upper rounding portion of the letter on the right is composed of an inclined line, followed by a vertical line, and this in turn by an inclined line. In the K and X the right-hand portion

45 of the letters is composed of a heavy line inclined in one direction, meeting a heavy line inclined in the opposite direction. In the Y the right-hand portion of the letter is composed of the heavy inclined line, followed by the

50 heavy vertical line; and in the Z the right-

hand portion of the letter consists of a short heavy vertical line, followed by a heavy inclined line, followed upon the right by a short horizontal line.

The faces of the letters are ornamented by a 55 series of fine horizontal lines, a space being left between these lines and the letter proper on all sides, so that the letter presents the appearance of a block-letter.

The character of the design is preserved in 60 the numerals.

The present design differs from the design for which Letters Patent were granted me December 12, 1882, in that the up-and-down portions of the letters are not concaved upon 65 the left, as therein shown, and that the horizontal lines do not extend upon the left of the up-and-down portions. Further, the present design does not show the triangular terminations, as shown in the E, F, K, L, M, N, S, T, 70 U, V, W, X, Y, and Z; and the design shown in Letters Patent No. 13,474 is more Roman in design than the present design. It differs from the design shown in Patent No. 10,290, to Bruce, November 6, 1877, in that the letter 75 of Bruce is slightly concaved upon the left of the up-and-down portion, no space is found between the outline and the shading on the right and below, the heavy shade is followed by a lighter shade, and the letter is 80 more of a Gothic in character than the present letter presented, which is clearly a block-letter.

Having now described my invention, I claim—

The design for a font of printing-type, as 85 shown and described, the same consisting of an open-face letter composed of a light line upon the top and left hand and a heavy line upon the right hand and bottom, these lines in the greater part of the letters shown not 90 departing from a right line, the C, G, O, Q, and S having the left-hand portion composed of an inclined line, forming a continuation of the top line, followed by a vertical line, and this in turn by an inclined line joining the 95 heavy line below; the U having the lower part of its left-hand portion inclined, as shown; the X having the left-hand portion of the letter composed of two lines inclined in opposite directions, meeting about centrally; the up- 100

(over)

per portion of the Y inclined upon the left, as shown; the left hand portion of the Q inclined, followed above and below by a short vertical line connecting with the light line above and the heavy line below; the D, O, Q, S, and U having the right hand portion composed of an inclined line, followed by a vertical line, succeeded by an inclined line, and this formation characterizing the upper and lower portions of the C and G upon the right; the rounding portions of the B and R similar, but joined in the center; the upper rounding portion of the P on the right formed of an inclined line, followed by a vertical line, and this in turn by an inclined line; the right-hand portion of the K and X composed of a heavy line inclined in one direction, meeting a heavy line inclined in the opposite direction; the right portion of the Y composed of the heavy inclined line, followed by the heavy vertical line; the right-hand portion of the Q composed of a short heavy vertical line, followed by a heavy inclined line, followed on the right by a short horizontal line; the face of the letters ornamented by a series of fine horizontal lines, a space being left between these lines and the letter proper, so that the letter presents the appearance of a block letter, and the character of the design preserved in the numerals.
